UNITED STATES PATENT OFFICE

136,649

DESIGN FOR A REVERSIBLE CAP

Milton A. Dannenberg, Chicago, Ill.

Application January 20, 1942, Serial No. 105,334

Term of patent 14 years

To all whom it may concern:

Be it known that I, Milton A. Dannenberg, a citizen of the United States of America, residing in the city of Chicago, in the county of Cook and State of Illinois, have invented a new, original, and ornamental Design for a Reversible Cap, of which the following is a specification, reference being had to the accompanying drawing, forming a part thereof.

Fig. 1 is a side perspective view of a reversible cap showing my new design, with the flap folded inside,

Fig. 2 is a similar view of the cap shown in Fig. 1, with the flap in unfolded position,

Fig. 3 is a similar view with the flap folded over the cap,

Fig. 4 is a front perspective view of the cap shown in Fig. 1, and

Figs. 5, 6, 7 and 8 are views respectively as Figs. 1, 2, 3 and 4, but with the cap reversed.

The characteristic feature of my design resides in the combination on the reversible cap disclosed of the specific bows on the faces of the cap, said bows being two-toned in conformity with the faces of the cap, as shown.

I claim:

The ornamental design for a reversible cap, substantially as shown and described.

MILTON A. DANNENBERG.
